No. 1243.

Henry S. Hubbell & Thomas H. Wood, of Buffalo, N.Y.
Letters Patent No. 1243. Dated May 15, 1860.

The schedule referred to in these Letters Patent and making part of the same.

To all whom it may concern:

Be it known that we, Henry S. Hubbell of the City of Buffalo, County of Erie and State of New York, and of Thomas H. Wood, of the City of Utica, County of Oneida and State aforesaid, have invented or produced a new and original design for Stove plate, and we do hereby declare that the following is a full and exact description of the same, reference being had to the accompanying photograph, and the letters of reference marked thereon -

Figure 1, is a perspective view of the Stove.

Letter A, is the Top plate. B. one of the oven sides both being the same, C. one of the oven doors, both being the same, D.D. the front of the Stove, E.E. the front doors, F. the end or fire door, attached to the side G. of the Stove, G. the oven top.

What we claim as our invention or production, and desire to secure by Letters Patent, is the general design and configuration represented in the accompanying photograph.
